UNITED STATES PATENT OFFICE.

PHILIP A. BECKER, OF NEW YORK, N. Y.

REMOVABLE DISPLAY-LID.

1,107,643.

Specification of Letters Patent. Patented Aug. 18, 1914.

Application filed August 1, 1913. Serial No. 782,498.

To all whom it may concern:

Be it known that I, PHILIP A. BECKER, a citizen of the United States, and a resident of New York, borough of Brooklyn, county of Kings, and State of New York, have invented a certain new and useful Improvement in Removable Display-Lids, of which the following is a full, clear, and exact specification.

10 This invention relates to a class of lids, or devices adapted to be used in conjunction with cigar boxes, or the like.

My invention has for its object primarily to provide a display lid designed to be applied especially upon forms of cigar boxes having the side walls of the body thereof projecting some distance above the front wall, and wherein is employed a frame provided with a filler adapted to be seated upon 20 the top edge of the front wall of the box between its upwardly projecting side walls, whereby air, or dust may be prevented from damaging the contents by passing through the space between the front wall and the 25 display lid when positioned upon the open top of the box.

Another object of the invention is to arrange the filler whereby it may serve as a retainer for holding a transparent plate in 30 the frame of the lid; and still another object of the invention is to provide a form of frame having a depending flange with a flared marginal edge for permitting the frame to be freely guided over the top of the 35 box as well as closely fitting the walls of the box when closed thereupon.

A further object of the invention is to provide a plurality of prongs which may be struck out of the depending flange and disposed inwardly thereof for supporting the transparent plate in the frame as occasion 40 requires.

With these and other objects in view, the invention will be hereinafter more particularly described with reference to the accompanying drawing which forms a part of this specification, and will then be pointed out in the claims at the end of the description.

In the drawing, Figure 1 is a perspective 50 view, partly broken away, of one form of display lid embodying my invention as applied to a cigar box. Fig. 2 is a fragmentary view, showing in detail, a front elevational view of the display lid. Fig. 3 is a fragmentary view, showing in detail, a front eleva-

tion of a slightly different form of the display lid. Fig. 4 is a fragmentary view, showing in detail, still another form of the display lid. Fig. 5 is an enlarged fragmentary section, taken on the line I—I of Fig. 60 1. Fig. 6 is an enlarged fragmentary section, taken on the line II—II of Fig. 2. Fig. 7 is an enlarged fragmentary section, taken on the line III—III of Fig. 3. Fig. 8 is an enlarged fragmentary section, taken 65 on the line IV—IV of Fig. 4, and Fig. 9 is a section taken on the line V—V of Fig. 1.

The removable display lid has a frame 10 adapted to be movably applied upon the open top of preferably well-known forms of 70 cigar boxes the bodies of which are made with side walls 11 and 12 of greater widths than the front wall 13 so that the upper edges of said side walls extend some distance above the front wall. A space, as 14, is 75 thereby provided above the upper edge of the front wall 13, and between the projecting portions of the side walls 11 and 12, and in this space is seated the hinged lid 15 of the box, when closed thereupon.

The frame 10 has side walls 16 and 17 and a front wall 18, each of which is substantially the shape of an inverted L, as viewed in cross-section, whereby a top flange 19 and a depending flange 20 are provided. 85 By providing the side walls and the front wall of the frame of this form, the frame is susceptible of being made to fit over the top edges of the side walls and the front wall of the box in a manner so that the depending flanges 20 of the frame will be in 90 close movable engagement with the walls of the box when the frame is closed thereon, and to permit the frame to be guided to a closed position upon the body of a box without contacting with the upper edges of its walls the free edge of the depending flange 20 of the side walls and the front walls of the frame is flared outwardly, as at 21.

Serving to prevent the contents of the box 100 being damaged by contact with air, or dust passing through the space 14 under the depending flared flange 20 when the frame is closed upon the box, upon the inner surface of said flange is provided a filler, as 22. 105 The filler 22 may be in the form of a rod, as Fig. 1, which is adapted to rest upon the top edge of the front wall of the body of the box, and said rod is of sufficient length to fill the space 14 between the side walls 110

of the box. In Fig. 3 is shown the filler as being formed by vertically slitting the depending flange 20 of the front wall of the frame adjacent to its ends, and curving, as 5 at 24, the part of the flange between the slits inwardly of the frame so as to fill the space 14 similarly to the rod 23. In Fig. 4 is illustrated the filler as being provided by longitudinally indenting inwardly a part, as 10 25, of the depending flange 20 so that the indented portion will closely fill the space 14 of the body of the box when the frame is closed on the box. The filler 22 of the frame of the display lid may also serve as a retainer for holding a plate of glass, or other transparent material, as 26, in the frame 10. In forming the frame 10 the filler, or retainer 22 is provided by being spaced from the top flange 19 of the front wall 18 of the 15 frame so that when the plate is fitted in the frame the front edge thereof will be seated in the space between the filler and said top flange. The transparent plate 26 may then be fastened against accidental displacement 20 in the frame 10 by a bar, or strip, as 27, which is substantially U-shaped in cross-section, and which is disposed in straddle arrangement on the rear edge of the transparent plate, and then soldered, or otherwise 25 secured to the ends of the side walls of the frame which are opposite to the front wall.

In conjunction with the employment of the filler, or retainer 22, I may use a plurality 30 of retainers, or prongs, as 28, or in some forms of the display lid the filler 22 may be dispensed with and the prongs used instead. The retainers, or prongs 28 are preferably provided by slitting in a V-shape suitable 35 portions of the depending flange 20 of one, or more of the walls of the frame, and then bending the prongs inwardly of the frame so as to be spaced from the top flanges 19 of the walls thereof. By arranging the 40 transparent plate in the frame so as to rest upon the prongs the plate will be secured therein for use in displaying the contents 45 of the box.

The frame 10 and its transparent plate 50 may be applied to a cigar box so as to be swung to open, or closed positions upon the open top of the body of the box by any suitable means, for instance by two sleeves, as 55 29 and 30, which are preferably alike in formation. Each of the sleeves 29 and 30 are substantially U-shaped, and said sleeves may be soldered, or otherwise held to either the bar 27, or to the ends of the side walls 16 and 17 which are opposite to the front 60 wall 18 of the frame 10. The sleeves 29 and 30 are sufficiently spaced apart to permit the side edges of the lid 15 of the box to be guided therein when the display lid is positioned at the top of the lid of the box, and 65 is then directed downwardly to the lower

part thereof. The display lid will thereby be arranged upon the open top of the body of the box for being swung to open, or closed positions when the lid of the box is manually moved in alternate directions 70 backwardly, or forwardly with relation to the body of the box.

In the foregoing description, I have embodied the preferred form of my invention, but I do not wish to be understood as limiting myself thereto, as I am aware that modifications may be made therein without departing from the principle, or sacrificing any of the advantages of this invention, therefore I reserve to myself the right to 75 make such changes as fairly fall within the scope of the appended claims.

Having thus described my invention, I claim as new and desire to secure by Letters Patent:—

1. In a display lid for a box provided with a hinged lid and a recess in the upper edge of the front wall and the rear wall of the box, the combination of a rectangular frame having three closed sides and an open rear side, the closed sides of said frame comprising a plate adapted to rest upon the top of the box, with an integral substantially S-shaped flange depending from said plate, and the upper recess thereof serving as a groove for reception of a transparent plate, and the lower curved portion of said flange serving as a guide whereby the frame may be freely directed downwardly over the edge of the box, and the rear or fourth side of said frame comprising a plate substantially the same as the top plate of the closed sides, said frame having two upwardly directed channelled members adapted to detachably and slidably engage the side edges of the lid of the box, whereby the display lid may be swung to an open or closed position on the box when the box is swung accordingly.

2. In a display lid for a box provided with a hinged lid and a recess in its upper edge of the front wall and the rear wall, the combination of a rectangular frame adapted to rest upon the top edge of the walls of the box, said frame comprising a flat plate and having upon its front side and on its two end sides a depending flange substantially S-shaped in cross section the upper curved part thereof serving as a groove for supporting the transparent plate within the frame, and the lower curved part thereof serving as a guide for the frame when directed downwardly over the top edge of the box, with a filler adapted to close the recess in the upper edge of the front wall of the box, and a plurality of prongs adapted for clamping the transparent plate whereby it may be secured within the frame and means for removably securing the display lid to the lid of the box whereby the

display lid may be swung to an open or closed position as the lid of the box is moved accordingly.

3. In a display lid for a box, having a recess in the top edge of one of its walls and provided with a hinged lid; the combination of a frame adapted to retain a transparent plate, and rest upon the top of the box so as to close the same, said frame comprising a rectangular frame, and having a flat plate adapted to rest upon the top of the edges of the transparent plate, a depending flange on each of the two end sides of said frame adapted to engage the ends of the transparent plate, each of said flanges having a plurality of prongs adapted to be bent upwardly and inwardly so as to clamp and retain the ends of the transparent plate in position within the said frame, and a depending flange substantially S-shaped in cross section, integrally formed upon the front side of the frame, the upper curved part serving as a groove for retaining the front edge of the transparent plate, and the lower grooved part serving as a guide for directing the frame over the edge of the box when it is applied thereto, with a filler adapted to fill the recess in the top edge of the front wall of the box, said filler being provided upon the inner surface of said S-shaped flange, and means for removably securing the frame to the lid of the box whereby the display lid may be swung to an open or closed position when the lid is moved accordingly.

4. In a display lid for a box having a recess in the upper edge of the front wall thereof, the combination of a frame adapted to retain therein a transparent plate, said frame having a flat top plate extending on the four sides of the transparent plate, two end flanges depending downwardly from the ends of the frame, and adapted to retain a transparent plate, and an integrally formed depending flange on the front of the frame, said front flange being substantially S-shaped in cross section, the upper and inverse curve of the flange serving as a groove for retaining the front edge of the transparent plate, and the lower and obversely curved portion of the flange serving as a guide whereby the said flange is directed over the edge of the box when

moved downwardly thereon, with a filler adapted to fill the recess in the upper edge 55 of the front wall of the box, substantially as shown and described.

5. In a display lid for a box provided with a hinged lid and a recess in the upper edge of its front wall, said display lid having a rectangular frame formed with three closed sides and an open rear side, the closed sides of said frame comprising a plate adapted to rest upon the top of the box, with an integral substantially S-shaped 65 flange depending therefrom, the upper recess thereof serving as a groove for reception of a transparent plate, and the lower curved portion of said flange serving as a guide whereby the frame may be freely directed downwardly over the edge of the box, and said frame having two upwardly extending channeled members adapted to detachably and slidingly engage the side edges of the lid of the box, whereby the display 70 lid may be swung to an open or closed position on the box when the box is swung accordingly, in combination with a filler on the inner surface of the S-shaped flange, and serving to close the recess in the upper 75 edge of the front wall of the box when the display lid is closed upon the box, whereby dust or the like may be prevented from entering the box through said recess of the front wall thereof.

6. In a display lid for a box provided with a hinged lid and a recess in the upper edge of its front wall, said display lid having a frame in which is mounted a transparent plate, and the frame having a depending flange on its front edge for being guided over the front wall of the box and over its recess, in combination with a metal rod on the inner surface of the depending flange, and serving to close the recess in 95 the upper edge of the front wall of the box when the display lid is closed upon the box, whereby dust or the like may be prevented from entering the box through said recess of the front wall thereof.

This specification signed and witnessed this thirty first day of July A. D. 1913.
